(57) **CLAIM**

The ornamental design for a fish toy, as shown and described.

DESCRIPTION

FIG. 1 is a perspective view of a fish toy in accordance with our design;

FIG. 2 is a right-side elevation view of the fish toy in accordance with our design;

FIG. 3 is a left-side elevation view of the fish toy in accordance with our design;

FIG. 4 is a top plan view of the fish toy in accordance with our design;

FIG. 5 is a bottom plan view of the fish toy in accordance with our design;

FIG. 6 is a front elevation view of the fish toy in accordance with our design; and,

FIG. 7 is a back elevation view of the fish toy in accordance with our design.

The broken-line disclosure of elements is understood to represent portions of the article in which the design is embodied, but which form no part of the claimed design.
